CLAIM

The ornamental design for furniture, as shown and described.

DESCRIPTION

FIG. 1 is a perspective view of furniture showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view of the furniture with the table tops shown at different heights; and,

FIG. 9 is another perspective view of the furniture with the table tops shown in alternate positions.

The broken line portion of the figure drawings is included to show portions of the article that form no part of the claimed design.
